ABSTRACT OF THE DISCLOSURE

An incandescent lamp having a tungsten filament surrounded by a light pervious envelope which utilizes certain of the hydrogen halides or chlorinated or brominated hydrocarbons to maintain a transport cycle between the tungsten filament and the inner wall of the envelope.

The invention relates to an electric incandescent lamp in which a tungsten filament is arranged in a bulb which is pervious to light. The bulb contains, in addition to an inert filling gas, a reactive transport gas the object of which is to prevent blackening of the bulb during burning by means of a regenerative cyclic process in which the tungsten which evaporates from the filament is converted into a volatile compound which decomposes in the proximity of or on the filament. In such a lamp the wall of the bulb is not blackened and the filament experiences no loss of weight. A tungsten filament is understood to include wires or coiled wires of tungsten.

The basic idea of a regenerative cycle to prevent blackening of the bulb of an incandescent lamp is already rather old. For example, a lamp has already been described which contains chlorine, bromine, or iodine as a transport gas and in which such a regenerative cycle was said to take place. However, in said lamp all metal components other than the filament, for example, supports and current supply wires and the comparatively cold ends of the filament had to be protected against the aggressive transport gas. In practice the protection of the said colder parts of the filament and of the other metal parts has proved to be a substantially insurmountable difficulty.

From later experiments it has appeared that a considerable improvement can be obtained when the geometry of such a lamp is chosen to be such that during burning of the lamp the comparatively cold ends of the filament and other comparatively cold tungsten parts in the lamp assume a temperature at which the said parts are not or only slightly attacked by the reactive transport gas.

When using iodine as the transport gas this requirement can rather easily be fulfilled structurally. When using iodine the construction of the lamp must be such that the comparatively cold parts of tungsten during burning assume a temperature above approximately 800° C. and the wall of the bulb assumes a temperature above approximately 250° C. This can be realized with a cylindrical bulb of quartz in which a filament of tungsten is arranged along the axis of the cylinder. Such a lamp has a greater efficiency expressed in lumen/watt than normal incandescent lamps have, while maintaining a substantially constant lumen/watt output during the whole life of the lamp. In these types of lamps, as is the case in normal lamps, the filament fuses at a comparatively hot point.

When iodine is replaced by chlorine or bromine which chemically are more active than iodine under otherwise the same conditions, attack of the comparatively cold tungsten parts in the lamp occurs to a greater extent. In

this case, tungsten crystals in the form of dendrites are formed at the ends of the filament, at the points where the filament is supported, and at the comparatively cold regions along the filament. In order to prevent attack by the transport gas the temperature of the entire filament in the presence of chlorine would have to be at least approximately 2500° C., and in the presence of bromine at least approximately 1700° C. during burning. Structurally this is difficult to realize with the present materials known for lamp manufacture.

The use of iodine as the transport gas provides many drawbacks. For example, it is difficult to introduce the exact quantity of iodine required in a lamp. The vapor pressure of iodine at room temperature is lower than the pressure required in the lamp for a proper functioning of the tungsten-iodine cycle. The filling is consequently performed usually at temperatures higher than room temperature. In that case it is necessary to accurately control the temperature of the filling device and of the lamp during filling. In addition, iodine is very reactive with respect to many metals; consequently the iodine filling device must consist of iodine-resistant material.

The tungsten-iodine cycle has been found to be particularly sensitive to all kinds of impurities. This sensitivity requires that all the materials used for the lamp have to be subjected to an extensive cleaning process. This is particularly true in the case of the tungsten filament.

The colour of iodine is undesired in certain cases, in the visible light an absorption of 4 to 5% occurs.

In order to mitigate the dosing difficulties it has already been proposed to fill lamps with hydrogen iodide (HI) which at room temperature is a gas. Since quartz is considerably permeable to hydrogen already, at a temperature of 300° C. the hydrogen would disappear from the lamp wholly or substantially wholly in the long run during burning of the lamp. The same effect would occur when the lamp is filled with hydrogen chloride or hydrogen bromide. After some time a tungsten-chlorine or tungsten bromine cycle would be obtained which, however, have the disadvantageous properties already described.

It is the object of the invention to mitigate a number of drawbacks associated with the use of iodine.

According to the invention this may be achieved by an incandescent lamp, comprising a tungsten filament, an envelope means containing said filament which has a low permeability to hydrogen, an inert filler gas within said envelope, and a gaseous mixture within said envelope selected from the group consisting of hydrogen and chlorine, or hydrogen and bromine.

The dosing of chlorine and hydrogen, and bromine and hydrogen is considerably simpler than of iodine, because these elements are gases or are volatile at room temperature or can be dosed via volatile or gaseous compounds which, in addition, are usually less reactive than iodine. These volatile or gaseous compounds are, for example, hydrogen chloride and chlorinated hydrocarbons which, in the case of hydrogen chloride in decomposition supplies chlorine and hydrogen, or in the case of the chlorinated hydrocarbons which, in decomposition form, chloroform, methylene chloride, ethylene dichloride, mixtures of these or of methane and carbon tetrachloride. The gaseous compounds hydrogen bromide and brominated hydrocarbons which on decomposition, supply bromine and hydrogen in the case of hydrogen bromide and bromoform, methylene bromide, methyl bromide, ethylene-dibromide, mixtures of these or of methane and other hydrocarbons with carbon tetrabromide in the case of the brominated hydrocarbons. By suitable choice of chlorinated or brominated hydrocarbon, if required together with hydrogen chloride or hydrogen bromide respectively

and/or chlorine or bromine and/or hydrogen a carbon getter may also be introduced into the lamp for gettering oxygen which element may disturb the regenerative cyclic process.

In practice it has been found that the ready functioning of the tungsten-hydrogen-chlorine and of the tungsten-hydrogen-bromine cycle is far less dependent on the purity of the materials from which the lamp is manufactured than is the case with the tungsten-iodine cycle. During the investigation which has resulted in the invention it has been found, for example, that tungsten filaments could be used with hydrogen chloride or hydrogen bromide as the reactive transport gas, which filaments could not be used with iodine as the reactive transport gas due to the existence of impurities, unless the cycle was activated by a small percentage of oxygen.

In addition it has been found in these experiments that the use of hydrogen iodide gives considerably worse results than iodine alone. This must be ascribed to the retarding influence of hydrogen on the tungsten-iodine cycle. This retarding action of hydrogen which consequently is not permissible when using iodine, has now been found to be particularly favourable when using chlorine or bromine. The drawbacks of the tungsten-chlorine and of the tungsten bromine cycle, namely the attack of comparatively cold parts of tungsten in the lamp, is sufficiently reduced in the presence of hydrogen. This is probably based on the fact that hydrogen chloride and hydrogen bromide do not attack solid tungsten and are not dissociated in hydrogen and chlorine or hydrogen and bromine respectively at the temperature of the comparatively cold parts of tungsten in the lamp. In a lamp containing hydrogen chloride, at the highest temperature only little hydrogen chloride is dissociated on the filament. The quantity of chlorine originating from this dissociation, however, may be sufficient to cause a cycle, by which blackening is prevented, to function when the quantity of hydrogen chloride in the lamp is sufficiently high. On the other hand when the quantity of hydrogen chloride is too large, blackening may occur also. The filling pressure of hydrogen chloride to be chosen depends in a complicated manner upon the temperature of the filament during burning of the lamp, on the geometry of the lamp and the filling pressure of the inert gas. However, for each type of lamp, the most favourable filling pressure of hydrogen chloride can be determined by simple experiment. However, it has been found that a favourable filling pressure usually lies between 7 and 14 mm. with respect to hydrogen chloride.

The reactive transport gas comprising hydrogen and chlorine need not contain accurately equivalent quantities of chlorine and hydrogen although this is to be preferred. A small excess of hydrogen may be favourable in certain conditions, while a small excess of chlorine need not have a disturbing influence. The best results are obtained when the ratio in gram atoms between chlorine and hydrogen in the gas mixtures lies between 4:5 and 5:4.

From the experiments which resulted in the invention it has been found, that optimum results may be obtained when at the beginning of life the lamp contains per cm.³ of bulb capacity between 0.35×10^{-6} and 1.00×10^{-6} gram atoms of hydrogen between and 0.35×10^{-6} and 1.00×10^{-6} of chlorine as such or in the form of a compound, for example, HCl or a chlorinated hydrocarbon.

In order to lose no tungsten by condensation of tungsten chlorides on the wall of the bulb, it is to be preferred to construct the lamp so that the wall of the bulb during burning reaches a temperature of approximately 350° C. or higher. Structurally, this can easily be realized. Since no blackening of the bulb occurs by condensation of tungsten on the wall of the bulb the distance between the filament and the wall of the bulb may be chosen to be very small.

In spite of the fact that the comparatively cold tungsten parts are substantially not attacked by hydrogen bromide,

it has surprisingly been found that the wall of the bulb of a lamp containing hydrogen bromide remains transparent. It has been found in addition that a lamp, the wall of the bulb of which is blackened by tungsten deposition, becomes entirely bright after having been filled with HBr or a HBr-supplying substance or mixture of substances after a short period of burning. The filling pressure of hydrogen bromide to be chosen depends upon the temperature of the filament during burning of the lamp, upon the geometry of the lamp and the filling pressure of the inert gas. However, the most favourable filling pressure of hydrogen bromide can be determined for each type of lamp with a restricted series of simple experiments. It has been found that this filling pressure is of minor criticalness and may lie between 1 mm. and 1 atm. HBr.

The reactive transport gas preferably contains non-equivalent quantities of bromine and hydrogen. An excess of hydrogen has been found to be very favourable for the life of the lamp. The best results are obtained when the ratio in gram atoms between bromine and hydrogen in the gas mixture lies between 1:1 and 1:7, although ratios to 1:10 and higher may give good results also; however, the absolute quantity of hydrogen may not become so high that the heat conductivity of the filling gas becomes too great as a result.

From the experiments which resulted in the invention, it has also been found that optimum results are obtained when at the beginning of life the lamp contains per cm.³ of bulb capacity between 1.5×10^{-7} and 1.05×10^{-5} gram atoms of hydrogen and 1.5×10^{-7} and 1.5×10^{-6} gram atoms of bromine as such or in the form of a compound as HBr or a brominated hydrocarbon, if required together with hydrogen and/or bromine.

In order to lose no tungsten by condensation of tungsten bromides on the wall of the bulb it is recommendable to construct the lamp so that the wall of the bulb during burning reaches a temperature of approximately 300° C. or higher. Structurally, this can be simply realized. Since no blackening of the wall occurs by condensation of tungsten on the wall of the bulb the distance between the filament and the wall of the bulb may be chosen to be very small.

Various measures, also in combination, may be used to prevent the loss of hydrogen which is detrimental to the life of the lamps which according to the invention contain hydrogen and a halogen chosen from the group consisting of chlorine and bromine.

(A) The lamp may be constructed so that during operation of the lamp at the voltage for which the lamp is designed the temperature of the filament is so high that the resulting life of the filament is already ended before the comparatively cold tungsten parts in the lamp are damaged as a result of chemical attack by chlorine or bromine in a manner which is detrimental to the life of the lamp. Such lamps may be used in optical systems in which it is not so much the long life of the lamp but rather the maintenance of a substantially constant luminous efficiency per watt during the whole life of the lamp that matters. Examples hereof are, for example, projection lamps, film lamps and photographic lamps, motorcar lamps and lamps for other special uses in which the filament temperature in general exceeds 3000° K. and the guaranteed life of the lamp usually is 15 to 150 hours. It has been found to be very readily possible however to manufacture lamps comprising hydrogen and bromine having life-times of 1000 hours and more.

(B) The bulb may also be manufactured from a type of quartz which is less permeable to hydrogen than is melted silicon dioxide. Alternatively, high-melting-point types of glass which do not pass hydrogen could be used.

(C) The bulb of a material which passes hydrogen may be provided in a bulb which does not pass hydrogen and the space between the two bulbs may be filled with hydrogen gas or a mixture of hydrogen and an inert gas.

(D) To maintain the desired ratio of hydrogen and

chlorine or bromine during the whole life of the lamp substances may be placed in the lamp which either can replace the hydrogen which is diffused away in and possibly through the wall of the bulb by supplying hydrogen or can bind the excess of chlorine or bromine which is formed as a result of the diffusing away of hydrogen or which combine those two functions. Alternatively, mixtures of substances showing one of those functions may be used.

A further advantage is that the hydrogen-chlorine and hydrogen-bromine compounds in question substantially always are colourless and that consequently no loss of light occurs by absorption.

In order that the invention may readily be carried into effect, it will now be described in greater detail, by way of example, with reference to the accompanying figures in which:

FIG. 1 is a cross-section of an incandescent lamp comprising an inner bulb and an outer bulb wherein the filament is arranged in the inner bulb and a hydrogen-containing gas is present between the inner bulb and the outer bulb, and

FIGS. 2 and 3 are also cross-sections of incandescent lamps.

FIG. 1 shows a partial cross-section of a filament lamp. A coiled filament 1 of tungsten which is connected to molybdenum plates 2 is arranged in a cylindrical bulb 3 of quartz. The filament is supported by the coiled tungsten supports 7 and 8. By means of the metal holders 4 and 5, which also serve as current conductors to the filament 1. The lamp is fixed in an outer bulb 6 of glass or another transparent and gas-tight material. The inner bulb contains a mixture of an inert gas and hydrogen chloride, the intermediate space between the inner bulb and the outer bulb contains a hydrogen-containing inert gas. In one embodiment the inner bulb had an inside diameter of $7\frac{1}{2}$ mm., a length of 150 mm., and the coiled tungsten filament has a length of approximately 150 cm. and a diameter of 1 mm. The filament had 225 v. applied thereto for a 1000 watt output with a luminous efficiency of 20 lumen/watt. The inner bulb was filled with a mixture of argon and hydrogen chloride which contained 1.6% by volume of hydrogen chloride (partial pressure hydrogen chloride 11.2 mm.) to a pressure of 700 mm. The space between the inner bulb and the outer bulb was filled to a pressure of 200 mm. with a mixture of argon and hydrogen of which the hydrogen content was varied between 0 and 1.0 Torr (0-0.5% by volume) according to Table 1 below which shows the life of the lamp in accordance with this percentage of hydrogen.

TABLE 1

Partial pressure H ₂ outer bulb	Life in hours	Remarks
0.....	500	Filament fused, supports attacked, bulb bright when filament fused.
0.1.....	>825	After 825 hours supports not yet attacked.
0.2.....	>825	Do.
1.0.....	>825	Do.

In none of the cases in which hydrogen was present in the outer bulb did attack of the supports occur which indicates that no detrimental quantity of hydrogen is lost during the burning time stated. In the absence of hydrogen in the outer bulb, the supports were rapidly attacked. The lamps burned in a horizontal position.

In the following experiments the load of the filament was chosen to be so that the life thereof was shorter than the time at which a variation of the chlorine-hydrogen ratio by loss of hydrogen occurred which was detrimental to the life.

FIG. 2 shows a cross-section of a so-called photographic lamp of 1000 watt, 3400° K. colour temperature at 225 volts and 32 lumen/watt luminous efficiency. The lamp comprises a bulb 3 of quartz having the following dimensions: inside diameter 7.5 mm., length 89 mm.,

coiled tungsten filament 1:1 length 1.32 m., diameter of the wire 172 μ , length of the coil 85 mm. Reference characters 7 and 8 indicate supports, and 2 indicates a molybdenum plate. The lamps were filled with a mixture of argon-nitrogen (8%) and 1.6% by volume of HCl, filling pressure 700 mm. The life was the same as that of an iodine lamp which contained 5 mm. of I₂ and was approximately 40 hours. The same was found when methylene dichloride was used with a filling pressure of 9 mm. The lamps were filled with a mixture of argon-nitrogen (8%) at a filling pressure of 600 mm. and varying quantities of bromine containing transport gas according to Table 2. The average life of comparable iodine lamps is approximately 27 hours.

TABLE 2

	Filling gas		Filling pressure in mm.					
H ₂ +Br ₂ :	H ₂	Br ₂	5.3	5.6	6.1	7.5	10.9	24.6
	Br ₂	Br ₂	5.3	5.3	5.3	5.3	5.3	5.3
Average life in hours.....	20	40	40	40	40	40	40	35
HBr.....	7	10.5	14	21	28	.....	.....	.....
Average life in hours.....	In all the cases between 30 and 40 hours						.....	.....
CH ₂ Br.....	10.5	.....	.....	.....	.....	.....	.....	.....
Average life in hours.....	30	.....	.....	.....	.....	.....	.....	.....

Experiments were also performed with so-called projection lamps, capacity approximately 1 cm.³, luminous efficiency 30 lm./watt at 100 watt and 12 volt. The life of comparable iodine lamp on an average 50 hours.

When filled with 4 atm. of krypton and quantities of HBr between 7 and 23 mm. an average life of 80 hours was found in all the cases.

FIG. 3 shows a partial cross-section of a filament lamp. A coiled filament 1 of tungsten which is connected to molybdenum plates 2 is located in a cylindrical bulb 3 of quartz. The filament is supported by the coiled supports 7 and 8 of tungsten. The lamp contains a mixture of an inert gas and hydrogen bromide or a compound supplying hydrogen bromide. The proportions of the bulb were: inside diameter 7.5 mm. and length 150 mm. The coiled tungsten filament had a length of approximately 150 cm., and a wire diameter of 1 mm. 225 volts were applied thereto to develop a 1000 watt output. The resulting luminous efficiency was 22 lumen per watt. The bulb was filled with a mixture of argon and hydrogen bromide to a pressure of 3 atm. After burning for 600 hours lamps which contained 7 and 14 mm. of HBr respectively had not yet fused and the supports were not yet attacked.

In this and the foregoing experiments the load of the filament was chosen to be so that the life thereof was shorter than the time in which a variation of the bromine-hydrogen ratio which is detrimental to the life occurred by loss of hydrogen.

What is claimed is:

1. An incandescent lamp comprising an envelope means of low permeability to hydrogen; a tungsten filament within said envelope, an inert filler gas disposed within said envelope, and a gaseous mixture disposed within said envelope selected from the group consisting of hydrogen and chlorine, hydrogen and bromine, chlorinated hydrocarbons and brominated hydrocarbons, wherein said envelope comprises a quartz glass bulb containing said filament, and an outer globe surrounding said bulb in spaced relation, said globe comprising a material permeable to light and having low permeability to hydrogen, and the space between said bulb and globe having a hydrogen filler, and means supporting said bulb within said globe.

2. An incandescent lamp comprising a substantially cylindrical envelope having a lower permeability to hydrogen than melted silicon dioxide; a coiled tungsten filament within said envelope having a linear axis substantially coincident with the centroidal axis of said cylindrical envelope, said envelope closely surrounding said filament so that the interior wall of said envelope is heated

during operation to a temperature in excess of 300° C.; an inert gas disposed within said envelope and a gaseous mixture disposed within said envelope for initiating and maintaining a regenerative cycle wherein the tungsten from the filament is vaporized, deposited on said inner envelope wall, combined with said gaseous mixture, returned to the region of the heated filament, separated from said gaseous mixture and redeposited on said filament, said gaseous mixture being selected from the group consisting of hydrogen chloride and the chlorinated hydrocarbons, wherein said gaseous mixture within said envelope is at a partial pressure within the range of 7 to 14 mm. and the ratio in gram atoms between chlorine and hydrogen is in the range between 4:5 and 5:4.

3. An incandescent lamp according to claim 2 wherein the number of gram atoms of hydrogen is within the range of 0.35×10^{-6} to 1.00×10^{-6} and the number of gram atoms of chlorine is within the range of 0.35×10^{-6} to 1.00×10^{-6} per cubic centimeter of envelope volume.

4. An incandescent lamp comprising a substantially cylindrical envelope having a lower permeability to hydrogen than melted silicon dioxide, a coiled tungsten filament within said envelope having a linear axis substantially coincident with the centroidal axis of said cylindrical envelope, said envelope closely surrounding said filament so that the interior wall of said envelope is heated during operation to a temperature in excess of 300° C.; an inert gas disposed within said envelope and a gaseous mixture disposed within said envelope for initiating and maintaining a regenerative cycle wherein the

tungsten from the filament is vaporized, deposited on said inner envelope wall, combined with said gaseous mixture, returned to the region of the heated filament, separated from said gaseous mixture and redeposited on said filament, said gaseous mixture being selected from the group consisting of hydrogen bromide and the brominated hydrocarbons, wherein said gaseous mixture within said envelope is at a partial pressure within the range of 1 mm. to 1 atmosphere and the ratio in gram atoms between bromine and hydrogen is in the range between 1:1 and 1:7.

5. An incandescent lamp according to claim 4 wherein the number of gram atoms of hydrogen is within the range of 1.5×10^{-7} and 1.05×10^{-5} and the number of gram atoms of chlorine is within the range of 1.5×10^{-7} and 1.5×10^{-6} per cubic centimeter of envelope volume.
